United States Patent Office.

JOHN A. THOMPSON, OF BUCYRUS, OHIO.

Letters Patent No. 79,031, dated June 16, 1868.

IMPROVEMENT IN MACHINE FOR CLEANING THE INTESTINES OF SLAUGHTERED ANIMALS.

The Schedule referred to in these Letters Patent and making part of the same.

Be it known that I, JOHN A. THOMPSON, of the town of Bucyrus, in the county of Crawford, and State of Ohio, have invented a new and useful Machine for Cleaning the Intestines of Slaughtered Animals, by drawing them between revolving brushes; and I do hereby declare that the following is a full, clear, and exact description of the construction and operation of the same, reference being had to the annexed drawings, making a part of this specification, in which—

Figure 1 is an inside view of my machine.

Figure 2 is a view of the main or crank-wheel and shaft, with the main cog-wheel at *a*, and a pinion at *b*, with a wooden roller surrounding it midway, having flanges at each end of said wooden roller, at *c c*.

Figure 3 is a view of a shaft, with a pinion at *d*, working in said crank-wheel at *a*, fig. 2, and revolving a larger cog-wheel at *e*, to give direction and velocity to the revolutions of the brushes, hereinafter mentioned.

Figure 4 is a view of the revolving brushes *A A*, having each a pinion at *ff* of the shaft, the cogs whereof work in each other, and the upper pinion, *f*, works in said wheel at *e*, fig. 3.

Figure 5 is a view of a shaft and cog-wheel, revolving the same on the end thereof at *g*, which is slowly turned by the pinion at *b*, fig. 2. On the centre of said last-mentioned shaft is an India-rubber covering, at *h* which revolves with the shaft.

Figure 6 is a view of a revolving shaft, having, midway thereon, a ridged or rugous band of wood, at *i*, fastened to and revolving with it in contact with said India-rubber band at *h*, fig. 5.

Figure 7 is a view of a guide and spreader, hooked on the rear end of the box containing the machinery, passing between said revolving brushes, and kept to its position at the forward end, near said rubber and wooden rollers, by two iron stakes set in the bottom of the box containing said machinery, and projecting up to the proper height between said revolving brushes and rollers.

Figure 8 is a hinged partition, of tin or other sheet metal, serving as a guard for said rollers.

To enable others skilled in the art to make and use my invention, I will proceed to describe its construction and operation.

I use a water-tight box of the proper size, say about three feet long, about ten inches wide, and about eight inches deep, and having set the wheels and shafts aforesaid to their proper positions, as shown in the drawing, the guide, fig. 7, is unhooked, and out of the machine, the intestines are turned inside out in the ordinary manner, and drawn on the guide, fig. 7. Said guide, with the intestines thereon, is put to its position aforesaid in the box; the crank is first turned backward so the brushes will draw through between them the end of the intestine; then the pinion at *d*, fig. 3, which is made to slide on its shaft, is momentarily slid out of gear; so the brushes cease for the time to revolve, the crank is turned forward, and the end of the intestine introduced between the rollers at *h* and *i*, figs. 5 and 6, which thereafter hold it; the pinion is then slid back to its position with said crank-wheel, fig. 2. The crank is then turned forward. The pinion, shaft, and wheel, fig. 3, turn the upper brush, *A*, by pinion *f*, which in its turn revolves the lower brush by means of the pinion *f*, on the end thereof. The front intestine is carried between said revolving brushes, and having been passed between said rubber and wooden rollers at *h* and *i*, figs. 5 and 6, said rollers, by their revolutions, draw said intestine constantly and regularly forward, pulling the same along between said revolving brushes. The end is taken by the hand of the operator at first, and passed over said wooden roller on said shaft at *c c*, fig. 2, pointing forward, and thereafter the intestines are carried over said partition and guard, fig. 8, and delivered in a cleansed state into a separate apartment, and by means of said guard are kept clear from clogging the machinery.

The box is first nearly filled with water, and the rapid revolutions of the brushes *A A* thoroughly clean the intestines, and deliver them in a suitable condition for sausages, Bolognas, or stuffed puddings.

I construct my brushes as shown, by bolting two flat or slightly-rounded brushes on each side of said shafts, at *A A*, fig. 4, in preference to cylindrical brushes, for the reason that they allow the intestines to pass more freely. The guide and spreader, fig. 7, serves to present a flat surface of the intestines to said brushes, although the machine works well without said spreader.

What I claim as my invention, and desire to secure by Letters Patent, is—

1. The cleaning of the intestines of animals by revolving brushes, substantially as herein described.
2. The cleaning of the intestines of animals by machinery, which operates to draw the intestines through between contiguous revolving brushes, by means of contiguous rollers, substantially as herein described.
3. The driving-wheel *a*, pinion *d*, grooved or flanged roller *e*, gear-wheel *e*, gum roller *h*, fluted roller *i*, and brushes *A A*, when arranged, combined, and operated substantially in the manner herein shown and described, for the purpose set forth.

JOHN A. THOMPSON.
